DAVID H. HAWES, OF BRIDGEPORT, CONNECTICUT.

FOUNTAIN SHAVING-BRUSH.

1,056,538.

Specification of Letters Patent. Patented Mar. 18, 1913.

Application filed November 23, 1911. Serial No. 662,001.

To all whom it may concern:

Be it known that I, DAVID H. HAWES, a citizen of the United States, residing at Bridgeport, county of Fairfield, State of Connecticut, have invented an Improvement 5 in Fountain Shaving-Brushes, of which the following is a specification.

This invention relates to fountain shaving brushes; that is brushes provided with 10 a reservoir for liquid soap and with means for controlling the flow of the liquid soap to the bristles or brush proper, and has for its object to provide a brush of this character which shall be simple and inexpensive to 15 produce, easy to fill, non-leaking, easy and sure in operation and practically impossible to get out of order.

With these and other objects in view I have devised the novel fountain shaving 20 brush for liquid soap, of which the following description in connection with the accompanying drawing is a specification, reference characters being used to indicate the several parts.

25 Figure 1 is a longitudinal part sectional view illustrating the construction and operation of my novel brush, the parts being in position to feed soap; Fig. 2 is a longitudinal elevation, partly broken away corresponding therewith, the brush head having been given a partial turn to close the feed 30 holes; and Fig. 3 is a section on the line 3—3 in Figs. 1 and 2, the feed holes being closed.

35 10 denotes a reservoir for liquid soap which is made of suitable shape and size to form a convenient handle for the brush. The reservoir is open at one end, is provided with a threaded hub 11 and is closed by a 40 screw cap 12, the closed end of said cap being provided with a cylindrical extension as shown.

13 denotes the bristles or brush proper and 14 the brush head in which the butts of 45 the bristles are secured in any ordinary or preferred manner as by compacting them in a mass of cement. The brush head is provided on the side opposite the bristles with an annular flange forming a circular recess 50 15 which receives the outer end of the screw cap closely. The face of the screw cap is provided with holes 16, two in the present instance, which are shown on opposite sides of the center and inclining from the inner 55 side of the cap toward the center. The brush head is provided with ducts 17 hav-

ing the same angle of inclination as holes 16 and adapted to be placed in alignment therewith. Ducts 17 in the brush head lead directly into a recess or pocket 18 formed 60 within the inner end of the brush proper.

The brush head and brush are secured to the screw cap by means of a bolt 19 having a head engaging the face of the brush head within recess 18 and extending through the 65 brush head and through the screw cap and extending a sufficient distance within the reservoir to provide space for a relatively strong spring 20, one end of which bears against the screw cap the other against a nut 21 on the bolt. This spring in practice 70 is made sufficiently strong to hold the brush head closely in contact with the screw cap so as to prevent leakage of the soap, also to retain the brush head in any position to which it may be rotated, (a certain amount of power being required to overcome the pressure of the spring) and also to take up 75 any wear of the parts so that the brush will remain non-leaking when closed no matter 80 in what position it may be placed.

It is of course immaterial so far as the principle of the invention is concerned how many corresponding holes and ducts are provided in the brush head and the screw 85 cap or just what amount of rotary movement is permitted to the brush head and brush. In the present instance, I have shown the screw cap as provided with a stop pin or projection 22 which lies in a slot 23 90 in the brush head. The slot is shown as long enough to permit about a quarter rotation of the brush head relatively to the screw cap, although but a slight movement is required to open and close the feed holes; that 95 is to place the ducts in the brush head in alignment with the feed holes in the screw cap.

As is clearly shown in Fig. 1 of the accompanying drawings, the bolt 19 is unthreaded excepting at its inner end portion so that there is no binding engagement of the said bolt with the cap and brush-head. This causes the brush-head to have a smooth 100 surface to rotate on, and such rotation is opposed by the clamping pressure exerted by the spring 20. By this means, the brush 105 can be readily rotated manually, but accidental rotation is prevented.

The operation is as follows: To fill the 110 reservoir, it is inverted from the position shown in Fig. 1, the screw cap and with it

the brush removed, the reservoir replenished with liquid soap and then the screw cap is returned to place. For use in shaving, it is simply necessary to hold the bristles downward, give the brush head sufficient rotary movement to place the ducts in alinement with the holes in the screw cap and then give the brush a quick motion or jerk downward, which motion may or may not be repeated. If the ducts and feed holes are fully in alinement, a single motion or jerk of the brush will ordinarily cause sufficient liquid soap to feed to the brush for a single use. The brush head is then turned 15 in the opposite direction sufficiently to close the feed holes. Should more soap be required, the brush head is turned sufficiently to partly or wholly open the feed holes by placing the ducts in alinement therewith and giving the brush another jerk downward 20 and then closing the feed holes as before. The bristles may or may not be dipped in water before using in accordance with the preference of the user. After use, the brush should be washed and dried in the usual manner. The brush needs no care other than any shaving brush should receive in the interests of sanitation and will operate perfectly until the liquid soap in the reservoir 25 is exhausted. Refilling takes but a moment's time and places the brush again in condition for a long period of use.

In practice, the stop pin and slot 23 are

so located and proportioned relatively to each other that when the stop pin engages 35 the one end of the slot the feed holes in the screw cap will be wholly open, in which position of the parts a single moderate downward jerk of the brush will supply ample soap for a single use, after which the brush 40 head is turned backward to close the feed holes, in which position the parts remain until next required for use.

Having thus described my invention I claim:

A fountain shaving brush comprising a reservoir open at one end, a removable cap closing said open end and having outlet openings, the closed end of said cap being provided with a cylindrical extension, a rotatable brush head having an annular flange at one edge and surrounding said cylindrical extension, said brush head having outlet ducts adapted to coincide with said outlet openings, a pivot bolt passed through said brush head and said cap, a nut adjustably carried by said bolt, a spring interposed between said nut and said cap, and means for limiting rotation of said brush head.

In testimony whereof I affix my signature in presence of two witnesses.

DAVID H. HAWES.
